[57] CLAIM

The ornamental design for a ball holder, as shown and described.

DESCRIPTION

FIG. 1 is a front perspective view of a first embodiment of my ball holder;

FIG. 2 is a front elevational view thereof;

FIG. 3 is a top plan view thereof;

FIG. 4 is a right side elevational view thereof;

FIG. 5 is a back elevational view thereof;

FIG. 6 is a left side elevational view thereof;

FIG. 7 is a bottom view thereof;

FIG. 8 is a front elevational view of a second embodiment of the ball holder of FIG. 1; and,

FIG. 9 is a right side elevational view of the second embodiment of the ball holder of FIG. 8, the left side elevational view being a mirror image thereof.

FIG.1

FIG. 3

FIG. 4

FIG. 2
